(57) **CLAIM**

The ornamental design for a low profile lighting system sensor as shown and described.

DESCRIPTION

FIG. 1 is a bottom right side perspective view of the low profile lighting system sensor;

FIG. 2 is a front side view thereof;

FIG. 3 is a right side view thereof;

FIG. 4 is a rear side plane view thereof;

FIG. 5 is a bottom side view thereof;

FIG. 6 is a top side plan view thereof; and,

FIG. 7 is a top front side perspective view thereof.

The left side view has been omitted as it is a mirror image of the right side view in FIG. 3. The broken lines in the
